UNITED STATES PATENT OFFICE.

GEORGE GAIL ALLENBAUGH, OF MANSFIELD, OHIO, ASSIGNOR OF ONE-HALF TO
THOMAS E. TAYLOR, OF MANSFIELD, OHIO.

TIMEPIECE.

Application filed June 16, 1921. Serial No. 477,979.

To all whom it may concern:

Be it known that I, GEORGE GAIL ALLENBAUGH, a citizen of the United States, residing at Mansfield, in the county of Richland and State of Ohio, have invented certain new and useful Improvements in Time-pieces, of which the following is a specification.

My invention relates to improvements in time pieces, such as watches, clocks and the like.

More specifically speaking, my invention relates to improvements in the face, dial and time indicating mechanism of such time pieces.

The primary object of my invention is to provide a substitute for and an improvement on the usual stationary dial and hour and minute hand mechanism through the provision of an improved face having suitable minute and hour or zone time indicators, together with improved movable or rotatably mounted concentrically arranged minute and hour indicating dials arranged in cooperative relation to said minute and hour zone indicators and to each other, whereby the time will not only be instantly and accurately indicated in the common time zone or meridian, but will be so indicated in the respective time zones or meridians thereby avoiding the necessity of constantly resetting the time indicating hands in passing into such various time zones or belts.

The improved rotatably mounted hour and minute dials are adapted to be arranged in cooperative relation to each other, as well as with respect to said relatively fixed indicators of the face of the time piece, and to be provided with suitable hour and minute numerals and graduations, the improved dials being adapted to replace the ordinary hour and minute hands and to be mounted on the ordinary hour and minute arbors of any ordinary time piece such as a watch or clock.

With the above mentioned and other ends in view, the invention consists in the novel construction, arrangement, and combination of parts, hereinafter described, illustrated in some of its embodiments in the accompanying drawings, and particularly pointed out in the appended claims.

Referring to the drawings, forming a part of this specification, Figure 1, is a view of the face part of an ordinary watch constructed in accordance with my invention.

Fig. 2, a view of the same with the lid or cover removed, or as applied to a watch of the open face type.

Fig. 3, a plan view of the face side of the lid or cover removed, and illustrating in particular the form of sight opening and relatively fixed-time-indicator or style which may be used in connection with a watch of the hunting case type.

Fig. 4, a plan view of the face side of the minute dial, detached.

Fig. 5, a similar view of the hour dial, detached.

Fig. 6, a front elevation of an ordinary time clock constructed in accordance with my invention and having its face equipped with time zone indicators.

Similar numerals of reference designate like parts throughout all the figures of the drawings.

The case or body of the time piece may be of any suitable and convenient construction and so likewise the internal mechanism. In the present instance, I have shown my improvements applied to either a watch of the closed face or "hunting case" type, as shown in Fig. 1, or if desired the improvements may be applied to a watch of the open face type as shown in Fig. 2, of the drawings. In Fig. 6, of the drawings I have shown my improvements incorporated in a time piece in the specific form of a clock.

The case 1, of the watch may be of any suitable and convenient form, and so likewise the body 1^a, of the clock.

When applied to a watch or a clock of the closed face type as shown in Figs. 1 and 6, of the drawings, the lid or cover 1^b or 1^c, as the case may be, is provided with a suitable sight opening, preferably of segmental form as shown and arranged at one side of the face 1^d, of the time piece. The sight opening 1^e, may either take the form shown in Figs. 1, and 3, of the drawings, or may comprise an outer elongated segmental portion 1^f, and a shorter opening 1^g, to expose the hour and minute dials, respectively, as shown in Fig. 6, of the drawings.

The face of the time piece is provided

- with a style or relatively fixed indicator 1^h, to indicate in conjunction with the hour and minute dials, and particularly the numerals and graduations thereon, the exact time.
- 5 When applied to a time piece of the closed face type as shown in Figs. 1, and 6, of the drawings, the style or indicator 1^h, may take the form of an extension or line 1^l, extending into the sight opening and preferably 10 formed as a part of a transparent covering 1^l, as shown more clearly in Figs. 1, and 3, of the drawings.
- The hour and minute dials 2, and 3, respectively, are concentrically arranged and 15 are provided with suitable hour and minute numerals and suitable graduations, the outer periphery of the minute dial 3, being preferably arranged immediately within the inner periphery of the outer dial 2, and the 20 hour and minute dials are adapted to be mounted on the usual hour and minute arbors 4, and 5, respectively, of the time piece, said movable or rotatably mounted dials 2, and 3, in the present instance being 25 provided with hub members 2^a, and 3^a, respectively, connected by arm or spoke members so that annular dial or rim members are provided in the present instance in close 30 relation to each other.
- As a means of providing suitable hour indicating zones and indicators adapted to indicate the respective time in the various zones or meridians without changing or 35 readjusting the time indicating dials or discs, the face of the time piece may be provided with a plurality of radially off-set hour or zone indicators 1^k, arranged in segmental form just outside of the outer periphery of the hour dial 2, as indicated in 40 Fig. 6 of the drawings, said zone indicators 1^k, being arranged at opposite sides of the main or median indicator or style 1^h, and the letters "P", "M", "C" and "E" designat-

ing respectively "Pacific", "Mountain", "Central", and "Eastern" time, respectively. 45

Having thus described some of the embodiments of my invention, without having attempted to set forth all the forms in which it may be made or all the modes of its use, what I claim and desire to secure by Letters Patent, is,—

1. In a time-piece, a face provided with circumferentially spaced time zone indicators and hour and minute indicating sight openings of segmental form, and concentrically 55 arranged juxtaposed annular hour and minute dials rotatable in said sight openings in cooperative time indicating relation to said time zone indicators and sight openings.

2. In a time-piece, a face provided with circumferentially spaced time zone indicators arranged in arcuate form and hour and minute indicating sight openings of segmental form extending along the inner periphery of said arcuate time zone indicators, 65 and concentrically arranged rotatably mounted hour and minute dials arranged in said segmental sight openings and passing said time zone indicators in cooperative relation thereto and to each other. 70

3. In a time-piece, a time-piece body provided with a sight opening and time and zone indicators on its face side, said zone indicators being of segmental form radially off-set from said sight opening and the latter comprising relatively long and short segmental portions, and hour and minute dials of annular form arranged to pass said zone indicators in cooperative time indicating relation thereto and within said relatively 80 long and short segmental portions of said sight opening.

In testimony whereof I have affixed my signature.

GEORGE GAIL ALLENBAUGH.
